DESIGN FOR A KITCHEN CABINET

Allen E. Stoltz, Dubuque, Iowa, assignor to Carr,
Ryder & Adams Company, Dubuque, Iowa, a
corporation of Iowa

Application April 15, 1935, Serial No. 56,397

Term of patent 3½ years

To all whom it may concern:

Be it known that I, Allen E. Stoltz, a citizen of the United States, residing at Dubuque, county of Dubuque, and State of Iowa, have invented a new, original, and ornamental Design for a Kitchen Cabinet, of which the following is a specification, reference being had to the accompanying drawing, forming part thereof, in which—

Figure 1 is a side elevational view;
Fig. 2 is a front elevational view; and
Fig. 3 is a view in perspective of a kitchen cabinet, showing my new design.

The dominant feature of the design is shown in full lines and consists in the front portion of the cabinet wherein the vertical edges are formed by a square corner having a narrow flat strip adjacent the forwardly rounded edges of the front section, combined with the sharp upper and lower square edges.

I claim:

The ornamental design for a kitchen cabinet, as shown and described.

ALLEN E. STOLTZ.
